GARMENT HANGER

Philip S. McLean, Bloomfield, N.J.
(233 Broadway, New York 7, N.Y.)

Filed Aug. 6, 1963, Ser. No. 76,118

Term of patent 14 years

(Cl. D80—8)

Fig. 1.

Fig. 2.

Fig. 3.

Fig. 4.

Fig. 5.

FIG. 1 is a front elevational view of a garment hanger showing my new design, the rear being a mirror image thereof.

FIG. 2 is a top plan view of the same.

FIG. 3 is a bottom plan view of the same.

FIGS. 4 and 5 are left and right end elevational views, respectively, of the same.

I claim:

The ornamental design for a garment hanger, substantially as shown and described.
